[57] **CLAIM**

The ornamental design for shipping container, as shown.

DESCRIPTION

FIG. 1 is an isometric view from above of a shipping container showing my new design;

FIG. 2 is a bottom plan view thereof, the top plan view being a mirror image thereof;

FIG. 3 is a front elevational view thereof, the rear elevational view being identical thereto; and

FIG. 4 is an end elevational view thereof, the opposite end elevational view being identical thereto.

FIG. 4

FIG. 2

FIG. 3
